A. NAGEL

CAMERA CASE

Filed Oct. 8, 1920

INVENTOR:

August Nagel

UNITED STATES PATENT OFFICE.

AUGUST NAGEL, OF STUTTGART, GERMANY.

CAMERA CASE.

Application filed October 8, 1920. Serial No. 415,692.

(GRANTED UNDER THE PROVISIONS OF THE ACT OF MARCH 3, 1921, 41 STAT. L. 1313.)

To all whom it may concern:

Be it known that I, AUGUST NAGEL, a citizen of the German Empire, residing at Stuttgart, Germany, have invented certain new and useful Improvements in Camera Cases (for which I have filed an application in Germany March 25, 1919; in England October 1, 1920, Patent No. 173,322; and in France September 30, 1920, Patent No. 525,238), of which the following is a specification.

My invention refers to photographic cameras, and more especially to the cases of roll film folding cameras. Its particular object is a casing of the kind aforesaid made all in one piece, with the only exception of the outer sidewalls, the inner casing for the folding mechanism as well as the film cartridge chambers and the rear wall of the camera consisting of a single strip of material such as sheet metal drawn or stamped and bent into shape, the flat portion of the said strip forming a continuation of one of the end walls of the inner casing, while its free end is applied against the free edge or else against the inner surface of the opposite end wall.

In the drawings affixed to this specification and forming part thereof, two modifications of a camera casing embodying my invention are illustrated by way of example. In the drawings—

Fig. 1 is a perspective view of one form. Fig. 2 is a like view of a modified form. Fig. 3 a longitudinal cross section of the casing shown in Fig. 1.

Fig. 4 is a plan view of the strip of material forming the casing shown in Fig. 1 the inner casing being already drawn or stamped, while the strip forming the continuation of an end wall of said inner casing is shaped ready for bending it into shape.

Fig. 5 is a longitudinal cross section according to Fig. 4.

Referring to Fig. 1 of the drawings, *a* is the inner casing designed for accommodating the folding parts such as the slide, the standards, the shutter, the stays etc. This said inner casing is formed by drawing or pressing into shape one end of a strip of

material (sheet aluminum or the like) the rear wall *c* of said inner casing which serves as the bellows frame, being stamped out simultaneously. The reference letters *a'*, *a''*, 55 designate the end walls and *g*, *g'* denote the side walls of the inner casing. The flat part of strip *d* is bent around the said inner casing from the rear, care being taken to leave room, next to the narrow end walls *a'*, *a''*, for the film cartridge chamber *k* and *m*, respectively, by bending said strip twice substantially in semicircular shape, while the intermediate portion *b*, which forms the outer rear wall, is flat and extends 60 in parallel with and at a slight distance from the rear wall *c* of said inner casing. The end wall *a''* is cut out at its free edge to give room for the free end *l* of strip *d* which is slightly narrower than the rest 65 and of a length about equalling the height of the said end wall *a''* and which is bent at right angles so as to lie flat against the inside of the said end wall (Fig. 3).

The outer casing, which thus surrounds 70 the inner one from the rear, is then closed at both sides by means of separate covers (not shown) with flanged rims which are removably connected with the casing.

In the modification disclosed in Fig. 2 75 the strip *d* is broader than the inner casing, a flange *f*, being formed at each side of said casing whereby narrow lateral chambers are formed for the accommodation of the mechanism actuating the inner parts of the 80 camera.

The space *h* intermediate the rear walls *c* and *b*, respectively, serves for the passage 85 of the flat portion of the film.

I claim:

1. In a roll film folding camera in combination, an inner casing and an outer casing, excepting the covers of said outer casing, made all in one piece.

2. In a roll film folding camera in combination, an inner casing and an outer casing, excepting the covers of said outer casing, formed of a single sheet metal strip.

3. In a roll film folding camera in combination, a substantially rectangular sheet metal casing and a sheet metal strip integral 100 with an end wall of said casing, said strip

surrounding said casing from the rear and its free end being joined to the opposite end wall of said casing.

4. In a roll film folding camera in combination, a substantially rectangular sheet metal casing and a sheet metal strip integral with an end wall of said casing, said strip

surrounding said casing from the rear and being twice bent into semicircular shape so as to form film cartridge chambers and its ¹⁰ free end being joined to the opposite end wall of said casing.

In testimony whereof I affix my signature.
AUGUST NAGEL.
